IMPULSE SENDING DEVICE

Original Filed Dec. 10, 1923

Herbert F. Obergfell

UNITED STATES PATENT OFFICE.

HERBERT F. OBERGfell, OF RIVER FOREST, ILLINOIS, ASSIGNOR, BY MESNE ASSIGNMENTS, TO AUTOMATIC ELECTRIC INC., OF CHICAGO, ILLINOIS, A CORPORATION OF DELAWARE.

IMPULSE SENDING DEVICE.

Original application filed December 10, 1923, Serial No. 679,517. Divided and this application filed August 28, 1925. Serial No. 53,039.

My invention relates in general to impulse sending devices of the dial type in which the impulses are generated and transmitted in definite series corresponding to definite digits 5 by successive manipulations of the dial.

More particularly, the invention relates to devices of the above type in which the action of the impulse mechanism is automatically controlled by a governor, and the impulses 10 are generated by the action of an interrupter, commonly and hereinafter termed the impulse cam, which latter as well as its governor are driven from the dial by means of appropriate gear transmission. In these de- 15 vices, and particularly when, as in the present instance, they are constructed in the form of a calling device for automatic telephone systems, many efforts have been made and various means devised to prevent sticking and 20 reduce binding and abrasion between gears.

The principal object of the invention is to provide an improved mechanism for accomplishing the above results. I have discovered that by the use of a laminated worm 25 gear consisting of a blank or layer of black fibre, or other suitable oil holding material, held between two phosphor bronze flanges or disks, I am able to practically entirely eliminate sticking and to reduce bind- 30 ing and abrasion to nil for all practical purposes.

Other new and improved features in the governor mechanism include a new and improved type spring in which the material 35 used is phosphor bronze, and the design used in fastening it to the worm shaft is new and improved, thus eliminating the previously used aluminum hub and practically eliminating breakage; a new and improved type of 40 governor fly-ball in which a piece of a gray fibre rod, or other suitable bearing material, is rounded off and inserted in the fly-balls to serve as a friction shoe and thus reduce abrasion between the fly-balls and governor cup; 45 and a new and improved type bearing in which the material is hardened steel and the design used to hold the parts in place is new and improved. This type bearing overcomes the objection to the previously used jeweled 50 bearings, i. e., of not having a convenient method of determining their freedom from flaws before being used, which flaws caused

pitting or breaking down of the bearing surface.

The present application is a division of 55 pending application, Serial No. 679,517, filed December 10, 1923, and features of novelty disclosed, but not claimed are covered by the original application referred to.

The above important features of the invention and other details will now be more fully described in the specification which is to follow, reference being had to the accompanying drawing, in which Fig. 1 is a front view of the device; Fig. 2 is a side view of the same, 60 looking in the direction of the arrow in Fig. 1, with one of the mounting lugs broken away for clearness; Fig. 3 is a rear view of the same; Fig. 4 is a perspective view of the telephone number and letter dial instruction of designation card, and dial escutcheon and escutcheon plate or adapter for same; Fig. 5 is an axial section of the governor mechanism taken on the line V—V of Fig. 2; Fig. 6 is a perspective view of the coil main 65 spring hub or support, and the shunt spring controlling lever; Fig. 7 is a perspective view of the laminated worm gear and pinion assembly; Fig. 8 is a view of the spring 26 on line A—A of Fig. 5; while Fig. 9 is a per- 70 spective view of the spring 26.

The impulse sending device illustrated comprises the usual finger hold dial 2 (as shown in Figs. 1 and 2) pivoted at a central point in the base plate 3 (Figs. 1, 2 and 3) 85 by means of a rod and having a coil main spring 4, one end of which is fastened to the rod or pin 5 to which the finger hold dial is fastened and which acts as a pivot for said dial, and the other end of which is fastened to a lug 6 on the under side of the base plate 3. The spring 4 acts to return the finger hold dial 2 to its normal position after the spring has been wound up by the rotation of the dial in a clockwise direction. A gear wheel is 90 mounted loosely upon the pivot rod 5 between the dial and the plate 3, as shown, for example, in U. S. Letters Patent No. 1,461,944 to Setter, dated July 17, 1923, which wheel has gear teeth around its circumference and also has ratchet teeth cut in its face lying adjacent to the dial 2. These ratchet teeth are spaced apart the same angular distance as the holes in the finger dial. Through an 95 100

opening in the dial 2 is placed a small metal dog which co-operates with the ratchet teeth on the gear wheel to rotate the latter with the finger hold dial in its return or counter-clockwise motion only until the dial reaches normal.

Co-operating with the gear teeth in the circumference of the gear wheel upon the pivot rod 5 is a pinion 7 (Figs. 2 and 7) 10 fixed to a shaft which is pivoted to the bracket 8 (Figs. 2 and 3) at one end and in an offset part of base plate 3 at the other end. Mounted on this same shaft is a laminated worm gear wheel 9, which will be explained 15 later, and a cam 10, shown in Figs. 2 and 3, having two wings adapted, when the shaft is rotated, to open and close contact of a pair of springs 11 and 12, which are usually used to send impulses over the well known two 20 wires of a telephone system to control automatic switches.

The worm wheel 9, as best shown in Fig. 7, consists of a blank or sheet of blank fibre held between two sheet phosphor bronze flanges, 25 all of which are punched out and driven on a shoulder of the pinion shaft. The shoulder has a flat surface cut on it to keep the wheel from turning and is tapered so that the wheel becomes held more secure as it 30 is driven on. The projecting shoulder is then staked to hold the wheel in position. Teeth are then cut on the bias to mesh with the governor worm 13, as best shown in Fig. 3, which drives the governor in the usual 35 well known manner.

The governor consists of the hardened steel worm shaft 13, as best shown in Fig. 5, which shaft is knurled to cause a tight fit of the round brass hub 20. The shaft is also 40 flattened at its ends and polished to bear against the hardened and polished chrome steel ball bearings 21 and 22. The ball bearing 21 receives very little wear and hence is merely driven tightly in place, while ball bearing 22 receives a thrust when the worm shaft is rotated and is therefore arranged as follows: In the screw end of the governor cup 23 is a hardened steel polished concave race 24, which is held stationary. The ball bearing 22 is smaller than the bore of the screw end of the governor cup and is held 50 loosely in place by the ground brass bushing 25 which is held stationary and has its bearing end slightly bent into a diameter less than that of the steel ball. The spring 55 26 is formed from a perforated blank having ample material surrounding the perforation to, by a drawing process, form a cup-like structure. The hub 20 has a collar at one 60 end over which the cup of the phosphor bronze spring 26 is tightly fitted. The spring is further held by prong staking or riveting the collar of the hub which extends slightly beyond it, while the hub is further 65 tightened to the shaft by ring staking the

end opposite the collar. To the ends of the governor spring 26 are riveted round brass governor fly-balls 27 and 28. These fly-balls are drilled out and in them are inserted conical shaped fibre friction shoes 29 and 30 ⁷⁰ which have their tops cut off and rounded, and are held securely in place by ring shoulder staking.

Three springs, 14, 15, and 16, as shown in Figs. 2 and 3, are provided and are what is known as the shunt springs; that is, these springs are allowed to close by bushing 17 as soon as the calling device leaves its normal position and are used to shunt the talking equipment at a subscriber's station in the usual well known manner. The bushing 17 is held on the end of the hard sheet brass shunt spring lever 18, as shown in Figs. 2, 3, and 6, by nicking the latter. The lever 18, (Fig. 6), fits over the collar on the top end of the hub 19, after the end of the main spring 4 has been placed in the groove which extends slightly below said collar, its inner projections fitting in said groove thus holding the main spring in place and keeping the hub ⁹⁰ from turning with respect to it. The top of the collar is then curled over or riveted to hold the lever securely in place.

The hub 19 is of sufficient length to almost touch against the stationary hub (not shown) of the base plate 3, which hold the rod or pin 5, and thus limits the distance the dial 2 can be pulled out with the spring in place. The bottom end of the hub is tapered so as to accommodate the decreasing diameter ¹⁰⁰ at the middle of the coil spring 4 as it is wound up or tensioned.

A dial instruction card 38, as best shown in Fig. 1, is mounted on the face of the dial 2 as follows: The dial escutcheon plate or adapter 31, as shown in Fig. 4, is made from soft sheet brass, or other suitable material, and has its edge turned over so as to rest securely on the face of the dial. It has a lowered bearing surface 32 and a lowered screw hole 33, the surface leading down to the latter being shaped to accommodate the head of the screw 37, which screw fastens the plate to the dial. The plate further has a projection 34 which fits into the hole 50 of the dial and holds it from turning, and cut out portions 35 and 36 to function with the dial escutcheon or cover ring 41 as will be explained later. The dial instruction card 38, made of white index bristol, or other suitable material, lies on top of the escutcheon plate 31 and has a projection 39 to function with the cover ring 41 as will also be explained later. The transparent celluloid cover 40 lies on top of the instruction card 38 and both are covered and held in place by the ring 41. The ring 41 is made from soft sheet brass, or other suitable material, and has its edge turned over to fit the escutcheon plate 31, the slight projections 42 and 43 being bent in to snap into ¹¹⁰ ¹²⁰ ¹³⁰

place and mesh with the cut out portions 35 and 36, respectively, of the plate 31. The cut out portion 44 accommodates the projection 39 of the card 38 and keeps the card from 5 turning as well as positions it with respect to the dial.

The operation of the device is as follows: In the well known manner the user of the device places his finger in the hole, through 10 which can be seen the desired digit, of the finger hold dial 2, and pulls the dial around in a clock-wise direction until the finger has encountered the stop 51, shown in Figs. 1, 2 and 3, at which time the finger is withdrawn. As 15 previously pointed out, the associated gears do not move during this operation, but tension is stored in the main coil spring 4, and the shunt springs are closed by the movement of lever 18. When the finger is withdrawn 20 the spring 4 exerts a force upon the dial 2 and rotates same back towards its normal position, causing the associated gear wheel (not shown) and pinion 7 to rotate with it. The shaft of pinion 7 thereby rotates the cam 10 25 to cause the springs 11 and 12 to be separated momentarily a number of times corresponding to the number of the finger hole into which the user's finger was inserted, and rotates the laminated worm wheel 9 to cause the 30 governor to regulate the speed of rotation of the parts in returning to normal. When the laminated worm wheel 9 is rotated it gives a rotating thrust to the worm shaft 13 due to its biased teeth. This rotating thrust causes 35 the chrome steel ball 22 to be pressed against the steel concave race 24 and become auto-

matically centered, thus providing an efficient bearing that wears uniformly due to being successively centered on different axes.

Having described my invention, what I 40 consider to be new and desire to have protected by Letters Patent will be pointed out in the appended claims.

What is claimed is:

1. In an impulse sending device, a governor 45 shaft, a hub having a collar at one end and fastened to said shaft, a flat winged governor spring having a hole in its center to fit over said collar and metal beyond in excess of the diameter of said hub drawn into the form of 50 a cup and fitting over said hub with said wings extending along said hub.

2. In a governor, a shaft, a spring perforated at its mid point, a hub on said shaft having a reduced portion adapted to register with 55 the hole in said spring, said spring having a substantial amount of material forming a cup fitting over a portion of said hub and having extensions, and speed controlling weights mounted at the ends thereof. 60

3. In a governor, a pair of springs formed from a single piece of metal, said piece of metal comprising a strip of phosphor bronze perforated at its mid point with the material immediately surrounding the perforation 65 formed into the form of the cup and with sectional continuations of the walls of the cup serving as said springs.

In witness whereof, I hereunto subscribe my name this 26th day of August A. D., 1925.

HERBERT F. OBERGFELL.
